UNITED STATES PATENT OFFICE.

EDWARD D. GLEASON, OF PHILADELPHIA, PENNSYLVANIA, ASSIGNOR TO
JULIUS WELLNER, OF PHILADELPHIA, PENNSYLVANIA.

SOUND-REPRODUCING MACHINE.

SPECIFICATION forming part of Letters Patent No. 732,292, dated June 30, 1903.

Application filed November 4, 1902. Serial No. 130,011. (No model.)

To all whom it may concern:

Be it known that I, EDWARD D. GLEASON, a citizen of the United States, residing at Philadelphia, in the county of Philadelphia and 5 State of Pennsylvania, have invented certain new and useful Improvements in Sound-Reproducing Machines, of which the following is a specification.

My invention relates to improvements in 10 sound-reproducing machines in which a stylus is automatically fed forward across the face of a record-disk, turned from engagement with the record at the end of its forward travel, and fed back to the starting-point while in an elevated position.

My invention consists in devices to cause 15 the sound-box to rotate and bring the stylus into engagement with the record with yielding pressure and in mechanism for disengaging the stylus from the record at the end of its forward movement and returning it in an elevated position to the starting-point, all of which will be hereinafter claimed and fully described.

Referring to the accompanying page of 20 drawings, Figure 1 illustrates a plan view of a sound-reproducing machine constructed after the manner of my improvements, with a portion of the casing broken away to more 25 clearly show some of the internal working parts; and Fig. 2 is a side elevation of what is illustrated in Fig. 1.

Referring to the reference letters of the 30 drawings, A represents an electric motor, the armature A' of which is mounted upon a driving-shaft B, which is provided with a worm-wheel C, operating the feed mechanism, and a bevel-wheel D, operating the turn-table carrying the record-disk. The turn-table E is 35 mounted upon a shaft E', which is provided with a bevel-gear E², meshing with the bevel-gear D, which, as before stated, is operated by the driving-shaft B. The record-disk E³ rests upon the turn-table E and is turned by 40 a pin e, projecting from the turn-table into an opening e³ in the record-disk.

F represents the sound-box, which is provided in the ordinary way with a diaphragm F', a stylus-lever F², and a stylus F³. The 45 sound-box F is fulcrumed to an arm G, which is connected to and forms part of a bracket G',

having bearings g and g', slidable upon a fixed rod H, supported by uprights n and n'. The arm G in moving forward and backward rests upon a rail R, which it is forced to engage by 55 reason of a fixed leaf-spring S, bearing against a projecting ledge s' on the under side of the bracket G'. As it is not an essential feature of my invention that the arm G should have any movement other than its forward and 60 backward movement upon the rod H, the rail R in some instances may be dispensed with and the bracket G guided upon a rod H, square in cross-section, instead of the round one I have illustrated.

The feeding of the sound-box and stylus forward is accomplished by means of the stylus engaging the helical groove of the record, and the stylus is caused to bear upon the record with yielding pressure by reason of its pivotal 70 connection with the arm G and a rod T, fulcrumed to the sound-box at one end and carried by a bearing t at the other, between which and the extreme end of the rod T is a spiral spring s. The return-feed for the sound-box 75 and its connecting parts is accomplished by the worm C engaging a worm-wheel I, which is provided with a segmental rack J, timed to engage at intervals a pinion K on a shaft K', which also carries a segment L to receive a 80 metal band L', one end of which is connected to the segment and the other end to the bracket G'.

After the sound-box has been carried forward by the engagement of the stylus with 85 the groove of the record and before the backward or return feed comes into play or at the instant it becomes operative it is necessary to disengage the stylus from the record. This is accomplished by placing on the under side 90 of the segmental rack J a cam M, which at a fixed time presses against a roller m', mounted in the end of a rod m, guided in a bearing m² and connected to a lever m³. The lever m³ operates a rocking frame O, which embraces 95 a shaft o, to which the lever m³ is secured, and uprights o' o', secured at the lower end to the shaft o and at the upper end to a rail o². The extreme end of the rod T, which moves the sound-box, is provided with a bearing t', in 100 which is supported a roller t², which, being at all times in the path of the rail o², is moved

to turn the sound-box and raise the stylus from the record when the rocking frame O is operated through the medium of its connecting parts and the cam M.

5 Having described my invention, what I claim, and desire to secure by Letters Patent, is—

1. A sound-reproducing machine, comprising a revoluble record-disk, a sound-box provided with a diaphragm and stylus, an arm carrying the sound-box journaled upon a fixed bar, a segment provided with a band, one end of which is connected to said arm, a pinion for turning the segment and a segmental rack connected to the driving mechanism and adapted to turn the pinion and thereby return the sound-box and stylus after they have been fed forward by the groove of the record, substantially as described.

10 2. A sound-reproducing machine, comprising a revoluble record, a sound-box provided with a diaphragm and stylus, the latter being operated in one direction by the groove of the record, a movable arm having a bearing in which the sound-box is free to turn, a rod fulcrumed to and adapted to turn the sound-box to release the stylus from the record at the end of its forward movement and a cam operated by the driving mechanism to move

15 30 said rod, substantially as described.

3. A sound-reproducing machine, comprising a turn-table provided with a record-disk, a sound-box provided with a diaphragm and

stylus carried in one direction by the groove of the record, a slideable arm, one end of which 35 is guided in a bearing and the other being arranged to form a journal in which the sound-box is free to turn, a segment provided with a band connected to said arm, a rack-and-pinion mechanism to operate the segment, to perform the return movement, a rod fulcrumed to the sound-box and arranged to turn the same and lift the stylus at the end of its forward movement, and a cam for operating the rod, substantially as described.

4. A sound-reproducing machine, comprising a rotatable record, a motor for operating the same, a fulcrumed sound-box provided with a diaphragm and stylus, an arm carrying the sound-box slideable upon a guide, a spring interposed between the arm and sound-box to cause the latter to turn and bring the stylus to bear upon the record with yielding pressure, so that the sound-box will be carried forward by the groove of the record, a cam 55 adapted to turn the sound-box and lift the stylus at the end of its forward movement, and a mechanism comprising a segmental rack and pinion to return the sound-box to its initial position, substantially as specified.

In testimony whereof I affix my signature in presence of two witnesses.

EDWARD D. GLEASON.
